UNITED STATES PATENT OFFICE.

CHARLES J. JENSEN, OF NORTH PLAINFIELD, NEW JERSEY.

LANTERN.

Application filed March 27, 1922. Serial No. 547,197.

To all whom it may concern:

Be it known that I, CHARLES J. JENSEN, a citizen of the United States of America, residing at North Plainfield, in the county of 5 Somerset and State of New Jersey, have invented certain new and useful Improvements in Lanterns; and I do hereby declare that the following is a full, clear, concise, and exact description of the invention, such 10 as will enable others skilled in the art to which it appertains to make and use the same.

This invention relates to improvements in lanterns, having for an object to provide a 15 lantern especially advantageous for use upon bicycles and similar vehicles, having a plurality of reflectors in the same arranged to emit light rays from the front, rear and one side wall of the lantern housing, there- 20 by affording visual warning to approaching vehicles to readily locate the bicycles so equipped and accordingly avoid the same.

It is likewise an object of the invention to provide a lantern with a novel form of 25 main reflector positioned in the lantern housing in a manner to reflect light rays emitted from the light source and to direct the same through the various lenses of the lantern in a most effectual manner.

30 Other objects will be in part obvious and in part pointed out hereinafter.

In order that the invention and its mode of operation may be readily understood by persons skilled in the art, I have in the accompanying 35 illustrative drawings and in the detailed following description based thereon, set out one possible embodiment of the same.

In these drawings:

40 Figure 1 is a horizontal section through a lamp constructed in accordance with the invention;

Figure 2 is a fragmentary vertical section therethrough taken on the line 2—2 of Figure 1, looking in the direction in which the arrows point;

Figure 3 is a detail in elevation of the main reflector;

Figure 4 is an elevation of one of the secondary reflectors;

Figure 5 is a reduced side elevation of a modified form of the main reflector; and

Figure 6 is a front elevation of the same.

Having more particular reference to the 55 drawings, in connection with which like characters of reference will designate cor-

responding parts throughout, the invention may be stated to comprehend a lantern Housing indicated by the numeral 1, preferably circular in cross section as shown in Figure 1 and having windows in the front and side walls thereof provided with correspondingly formed frames 2 adapted to receive lenses 3, 4, and 5 therein, such lenses being of different colors, as for example, the front lens being white, the lens 4 being green and the lens 5 red. A suitable light source, such as a liquid fuel burner or an electrical incandescent lamp 6 is arranged concentrically of the housing 1, as shown in the Figure 2, being adapted to have the light rays emitted therefrom directed through the lenses 3, 4 and 5, for an obvious purpose.

With a view towards providing means for the reflecting of light rays to the lenses 3, 4 and 5, I provide a main reflector indicated by the numeral 7, consisting of a metal body formed with a highly polished outer surface and having the lower portion thereof arranged with diagonally disposed or substantially V-shaped reflecting surfaces, while the upper portion thereof is concaved as at 8 and provides means for reflecting certain of the light rays emitted from the light source 6 forwardly through the front lens 3. This main reflector 7 is preferably secured in position by means of a metal strap 9 passing about its intermediate portion and having the opposite extremities thereof passed through openings in the rearward portion of the lamp housing 1, whereby they may be engaged with an object, such as indicated at 10, to which it is desired to secure the lamp, the outer ends of such strap being bent at right angles as indicated at 11 or otherwise formed to permit of such connection.

Secondary reflectors formed of sheet metal and having the outer surfaces thereof suitably polished are arranged within the housing 1 and as will be noted, are of substantially V-shaped formation in cross section, the marginal portions thereof being flanged as indicated at 13 whereby they may be secured to adjacent portions of said housing 1 as by soldering or similar fastening means, such secondary reflectors being preferably positioned at points in proximity to the opposite sides of the front window of the lamp housing 1 or the lens 3.

Because of the relative positioning of the

2
main reflector 7 and the secondary reflectors 12 within the lamp housing 1, it will be understood that certain of the light rays emitted from said lamp will be reflected 5 upon the V-shaped or diagonal lower portion of the main reflector and thus reflected outwardly through the lenses 4 and 5 arranged in the side walls of the housing. Others of the light rays will be reflected 10 from the concaved upper portion 8 of the main reflector and directed forwardly through the lens 3. Those light rays projected in a forward direction from the light source 6 will engage with the bevelled sides 15 of the V-shaped secondary reflectors 12 and in consequence, will be reflected therefrom through the front and side lenses 3, 4 and 5. In this way, it will be appreciated that maximum illumination will be provided by 20 the lamp through its light source 6 and in consequence, that the colored lenses 3, 4 and 5 will be rendered readily visible in darkness, enabling persons to readily locate the same.

25 The lamp will be found especially desirable for use upon bicycles, since, the forward

white lens 3 will permit of the illumination of the path being traversed by the vehicle, while the colored side lenses formed by it will offer ample warning or signals to vehicular traffic and pedestrians. 30

I claim:

In a lantern comprising a housing having windows in the front and side walls thereof, lenses positioned in each of said windows, a main reflector immovably positioned within the housing adjacent its rear wall intermediate of said side windows and in direct alignment with the front window, said reflector comprising a body substantially V-shaped in cross section in its lower portion and having one face of the upper portion thereof vertically curved and extending throughout its width at substantially right angles to the V-shaped lower portion of the same, and secondary reflectors fixedly secured within the housing at points in proximity to the opposite sides of the lenses in the front wall thereof. 35 40 45

In witness whereof I have hereunto set my hand. 50

CHARLES J. JENSEN.
